INSULATOR-SUPPORTING FIXTURE.

1,157,036.

Specification of Letters Patent. Patented Oct. 19, 1915.

Application filed August 8, 1914. Serial No. 833,779.

To all whom it may concern:

Be it known that I, CHARLES L. PEIRCE, Jr., a citizen of the United States, and a resident of Pittsburgh, in the county of Allegheny and State of Pennsylvania, have invented certain new and useful Improvements in Insulator-Supporting Fixtures, of which the following is a specification.

My invention relates to insulator supporting fixtures and particularly an improved fixture for supporting both the primary and secondary wires of an alternating current supply circuit.

Among the important objects of the invention are to provide an integral fixture on which both the primary and the secondary wires of a distribution system may be efficiently supported; to provide such integral fixture on which the primary wires may be supported in horizontal alinement and on which the secondary wires may be supported in vertical alinement; to provide such integral fixture on which pin type of insulators may be applied to support the primary wires and on which spool type insulators are vertically aligned to support the secondary wires; to provide a structure in which the insulators for the secondary wires are supported both at the top and bottom and at a sufficient distance from the supporting pole to insure adequate insulation; to produce a fixture which will require a minimum of pole space for its support and which can be fastened to the pole with a minimum amount of labor; to provide such construction and arrangement for the supporting arms that there will be no uneven sag of the wires or lateral swing of the arms when heavy wires or cables are applied to the insulators; and in general to provide a strong, rigid and light structure which will be better able to more efficiently support and take care of both primary and secondary wires.

The various features of the invention will be clearly understood by reference to the accompanying drawings in which—Figure 1 is a plan view; Fig. 2 is a side elevational view; Fig. 3 is a sectional view on plane 3—3, Fig. 2; Fig. 4 is a side elevational view showing a modified arrangement; Fig. 5 is a sectional view on plane 5—5, Fig. 4; and Fig. 6 is an underside view of a supporting arm.

In the fixtures shown the frame B is bent

up integral of sheet metal, preferably of channel shape cross section and comprises the vertical part 10 and the horizontal part 11 extending from the top thereof, the flanges *a* and *b* extending inwardly. Extending horizontally inwardly from the vertical part 10 are a plurality of supporting arms 12. In Figs. 1 to 3 these arms are of V-shape and bent from a single piece of stock metal, preferably channel bar. The bend of each arm is expanded to form a loop *c*, the limbs *d* and *e* directly adjacent the loop being brought together as indicated at *f* while the inner ends of the limbs are secured to the opposite flanges *a* and *b* of the part 10 to be secured thereto by rivets *g* or by welding. The limbs at *f* need not necessarily be secured together, but if desired rivets or welding could be resorted to at this point. The web *h* of the part 10 has a number of bolt holes 13 through which lag bolts or through bolts *i* may extend for fastening the fixture to a support such as a pole *p*. The web *h* may be concaved in order to more accurately fit the curvature of the supporting pole.

Extending through the vertical aligned loops *c* of the arms 12, is a bolt 14 for receiving spool type insulators *I*, the insulators resting on the supporting arms.

The horizontal part 11 of the fixture has a plurality of holes through its web for receiving the shanks of suitable insulator pins *j*. In order to secure the fixture against lateral swing braces 15 and 16 may be provided, these braces being secured at their outer ends to the opposite flanges of the part 11 as indicated at 17 and their inner ends being provided with bolt holes 18 by means of which they may be secured to the opposite sides of the pole. Under certain conditions only one brace would be necessary but under extra heavy service the two braces would be desirable. The braces shown are in the form of channel bars, but it is evident that flat bars or other forms may be used. The inner ends of the braces are also preferably rounded to more accurately fit the curvature of the pole.

The above construction forms a very strong but light fixture. The V-shaped supporting arms with their spread apart limbs secured to the opposite flanges of the part 10 are very rigid and will resist lateral strains, and the arms are mutually strength-

ened against sag by the interconnecting bolt 14 and the insulators I. The web of the part 10 being rounded to snugly fit the pole, the fixture can be very rigidly secured 5 to the pole even without additional braces 15, but when such braces are applied the fixture will support very heavy wires or cables without sagging or without swinging laterally.

10 In Figs. 4, 5 and 6 a modified arrangement is shown. The supporting arms 12 instead of being bent into shape from stock bars, are pressed or rolled integral from sheet metal. Each arm is of general V- 15 shape and comprises a V-shaped body 20 from whose edges extend the strengthening flanges 21 and 22. The arms extend with their bases into the vertical part 10 of the supporting frame B and the bases of the 20 flanges 21 and 22 are secured to the flanges a and b of the part 10 either by rivets 23 or by bolts, or by welding. In order to strengthen the arms and their support on the frame particularly against downward 25 pressure, the body 20 of each arm is offset upwardly a distance as indicated at m, and the inner ends of the flanges 21 and 22 are extended downwardly a distance in order to give greater bearing surface of the flanges 30 with the flanges of frame 10, the bolt or rivet holes through the arm flanges being then preferably near the tops of the flanges, the extended flanges below the bolts then acting more or less as struts or braces for 35 the arms. At its outer end each arm has a hole or passageway 24 for receiving the bolt 14 which supports the insulators I.

In practice the primary wires are supported on the pins on the horizontal arm of 40 the fixture while the secondary wires are supported on the insulators I, the top insulator preferably supporting a grounded neutral wire. The constructions above described are particularly strong and efficient 45 in supporting heavy secondary wires as the vertically extending and aligned spool insulators are supported both above and below by the supporting arms. Petticoat insulators on pins would not be sufficiently strong 50 to bear the strains of such secondary wires and the pins would readily give or break. The pin supported insulators on the horizontal arm of the fixture are, however, sufficiently strong, as primary wires are com- 55 paratively very light and there is usually only vertical strain on the pins. By having the vertical and horizontal parts 10 and 11 in the form of the integral frame B, much greater strength is provided than if such 60 parts were separated and bolted or otherwise detachably secured together. Furthermore, the cost of manufacture of such integral structure is a great deal less than where several parts are used.

65 I do not desire to be limited to the exact

forms, shapes and constructions shown as modifications may be made which would still come within the scope of the invention.

I claim as follows:

1. An insulator support comprising a vertical part having spaced apart flanges, a plurality of laterally extending supporting members each having a hole at its outer end to receive a bolt and secured at its inner end to the flanges of the vertical part, and a bolt 70 extending through the holes of the supporting members for receiving insulators.

2. An insulator supporting fixture comprising a supporting body having spaced apart flanges, supporting frames extending laterally from said supporting body, each frame being formed by bending a single piece of metal, the end of each frame being secured to the opposite flanges of the supporting body, and a rod detachably applied 80 to the various frames for receiving insulators.

3. An insulator supporting fixture comprising a body part in the form of a sheet metal channel, a plurality of supporting 90 arms each having a hole at its outer end and secured at its inner end to the opposite flanges of said body part, and a detachable insulator supporting rod engaging in the aligned holes of said arms.

4. An insulator supporting fixture comprising a supporting member in the form of a channel bar, a plurality of V-shaped supporting frames extending from said supporting member and each provided with a hole at its outer end, each frame being secured at its inner corners to the opposite flanges of said supporting channel member, and an insulator supporting rod having detachable engagement in the aligned holes of 100 said frames.

5. An insulator supporting fixture comprising a vertical supporting part having spaced apart parallel flanges, a tier of arms extending laterally and secured at their inner ends to said flanges, the outer ends of said arms being adapted to detachably receive a rod, said rod being adapted to receive and to confine insulators between the outer ends of said arms, and a horizontal 110 part extending from said vertical supporting part and overhanging said arms.

6. An insulator supporting fixture comprising a vertical supporting part having spaced apart parallel flanges, a tier of arms extending laterally and secured at their inner ends to said flanges, the outer ends of said arms being adapted to detachably receive a rod, said rod being adapted to receive and to confine insulators between the outer ends of said arms, and a horizontal 120 part integral with and extending from said vertical supporting part and overhanging said arms.

7. An insulator supporting fixture com- 130

prising a vertical section and a horizontal section, arms extending from the vertical section, a rod detachably secured to the outer ends of said arms and adapted to confine insulators between the outer ends of said arms, said horizontal section overhanging said arms, said vertical section being adapted to be secured to a support, and a brace secured at its outer end to the horizontal section and adapted at its inner end to be secured to the support.

8. In an insulator supporting fixture, the combination of a supporting body comprising a vertical and a horizontal section, said body being bent from a single piece of sheet metal of channel shape cross section, a tier of spaced apart supporting arms extending from the vertical section, each arm being bent into V-form from a single piece of metal, the inner ends of each arm being secured to the opposite flanges of the vertical section and each arm having a hole at its outer end, the aligned holes being adapted to detachably receive a rod for receiving and supporting insulators between the arms, the vertical section of the body being adapted to be secured by its web against a support, and a brace secured at its outer end to a web of the horizontal section and adapted at its inner end to be secured to the support to which the vertical section is secured.

9. In an insulator supporting fixture, the combination of a body comprising a vertical and a horizontal section, said body being formed by bending a single piece of sheet metal of channel shaped cross section and with its flanges extending inwardly, a tier of spaced apart supporting arms extending

from the vertical section, each arm being secured at its inner end between and to the opposite flanges of the vertical section, a rod detachably secured to the outer ends of the arms for receiving and supporting insulators between said arms, said horizontal section overhanging said arms, the vertical section being adapted to be secured by its web to a support, and a brace secured at its outer end to the horizontal section and adapted at its inner end to be secured to said support.

10. In an insulator supporting fixture, the combination of a body comprising a vertical and a horizontal section, said body being formed by bending a single piece of sheet metal of channel shaped cross section and with its flanges extending inwardly, a tier of spaced apart supporting arms extending from the vertical section, each arm being secured at its inner end between and to the opposite flanges of the vertical section, a rod detachably secured to the outer ends of the arms for receiving and supporting insulators between said arms, said horizontal section overhanging said arms, the web of the vertical section being concave to fit the curvatures of poles and having bolt holes, and a brace secured at its outer end to the horizontal section and adapted at its inner end to be secured to the support.

In witness whereof I hereunto set my hand this 28th day of July, A. D. 1914.

CHARLES L. PEIRCE, JR.
